AUTOMATIC WASHER COMPANY, OF NEWTON, IOWA, A CORPORATION OF DELA-
WARE

WRINGER

Application filed June 11, 1927. Serial No. 198,105.

This invention relates to wringers.

One of the objects of the invention is in the provision of a stamped steel wringer of such simple construction that same may be manufactured at a minimum cost.

Another object is in the provision of a stamped steel wringer fashioned in a simple and sturdy manner, same being adapted to be taken apart with the minimum of effort, 10 to permit replacement or repair to the rollers or pressure and release mechanism.

Still another object is in the provision of a stamped steel wringer mechanism comprising a quick release means fashioned in such 15 manner that the release portion thereof may be operated with much less effort than is ordinarily required.

A further object is in the provision of safety release mechanism for the pressure 20 applying means in the wringer, wherein the release member is much more sensitive than in the conventional wringer.

A still further object is in the provision 25 of quick release mechanism that is associated with the upper frame of the wringer in such manner that same is released in a substantially horizontal, rather than a vertical, manner, thereby permitting a much more sensitive adjustment of the safety mechanism.

An additional object is in the fashioning 30 of a stamped steel wringer, wherein the drain board is formed integrally with the wringer framework, thereby obviating a number of wringer parts, said wringer also comprising 35 a quickly detachable framing portion, which in turn carries the entire pressure applying mechanism and quick release mechanism, which is not only simple in construction, but operated with a minimum of pressure.

Other objects will appear in the following 40 specification, taken in connection with the annexed drawings, in which—

Fig. 1 is a plan view of my wringer, with 45 the safety mechanism in its released position;

Fig. 2 is a side elevation of the wringer, with portions thereof broken away for a more detailed elevational view of the safety release mechanism;

Fig. 3 is an end elevation of Fig. 2;

Fig. 4 is a plan view, from below, taken on the line 4—4 of Fig. 2;

Fig. 5 is a plan view, from above, taken on the line 5—5 of Fig. 3;

Fig. 6 is a plan view, from below, of the 55 wringer, showing the integral fashioning of the drain board with the wringer framing;

Fig. 7 is an end elevation of the wringer, with the upper frame removed, and

Fig. 8 is an opposite end view, with the 60 upper frame portion removed.

The present applicant has developed herein a stamped steel wringer, simple in construction, one having all of the advantages of even the most expensive wringers, and 65 associated with such simple structure a safety release mechanism of a much more sensitive nature than is found upon any wringers that are known in the trade today. With all the advantages of the sturdy stamped steel construction, the quick demountability of the 70 wringer, and the quick release mechanism, nevertheless, said wringer may be built at an extremely low cost.

In the drawings, it is found that the 75 wringer is made up of a lower frame portion and an upper frame portion. The lower frame portion comprises a stamped metal drain board 10, the side portions of which, namely 11 and 12, are formed integrally 80 therewith and provide the necessary guideways or receiving portions for the bearings of the wringer rolls.

To completely house the bearing portions within the guideways 11 and 12, it is necessary to attach thereto the lower end portions 13 and 14. These portions 13 and 14 may be secured to the bottoms of guideways 11 and 12 in any suitable manner. By stamping the drain board and the guideways 90 11 and 12 in one piece, the necessity of continuing the framing entirely beneath the drain board is obviated, thereby saving a considerable amount of material and without lessening the strength of the wringer. 95 The manner of mounting the wringer rolls 15 and 16 within the lower frame is conventional in all respects, except that in this instance, the lower frame is formed integrally with the guideways, there being disposed in 100

the guideways 11 and 12 bearing blocks which may be of wood or any other material and which have been designated herein 17, 18, 19 and 20. The portions 11 and 12 are slotted to permit the manual removal of both rolls as well as the bearing blocks containing same, this demountable feature being desirable in case of necessity of repair either to the wringer rolls or bearings connected thereto.

10 Detachably connected to the lower stamped metal frame and drain board, is an upper demountable frame 21, which is also of stamped metal, and is connected to the lower frame in the following simple manner. The side portion 11 has a catch portion or lug 22 projecting outwardly therefrom in a manner to engage an adjacent slot 23 in the upper frame 21. Upon the end piece 12 is also formed, or as a matter of fact, stamped therein, an outwardly projecting lug 24. This lug is provided with a vertical aperture 26 for the reception of a movable key 27. The upper end of the key 27 is bent inwardly to project into a slot 25 in the upper frame 21 and a registering slot in the lower frame 12. The aperture 26 is made wide enough to permit the key 27 to be moved outwardly from the frame members far enough to free its inwardly bent end from the slot 25.

15 The spring latch holding member 28 is stamped from the side portion 12 of the lower frame. The lower end of this latch holding member is bent inwardly, and the lower part of key 27 is bent so as to form a groove therein. This groove is engaged by the bent end of member 28 to releasably hold the key 27 in locking position. The strap 24 also serves to keep the key in place on the machine.

20 It is apparent from the above that when it is desired to remove the upper frame for repair to the upper wringer roll or the bearings thereof, it is necessary merely to pull back the key 27 out of the slots in the upper and lower frames against the pressure of the spring 28. This permits that side of the upper frame to be raised, and upon a slight sideward movement the slot 23 on the other side will be released from the lug 22 and the frame may be removed bodily. When it is desired to replace the upper frame, the slot 23 is positioned over the lug 22, the key 27 is drawn back, and the slot 25 is brought into register with the corresponding slot in the lower frame. The key 27 is then released and is forced into the slots by the pressure of spring 28. Thus the upper frame is positively locked to the lower frame. It is apparent that the connecting means not only provides a satisfactory connection between the two parts, but also one that is very simple and which requires a minimum of manual effort to operate.

25 The stamped upper frame 21 carries the

pressure-applying means, which in the present instance is a flat spring 29, disposed horizontally within the upper frame, and the end portions 30 and 31 thereof overlying the bearings for the upper wringer roll.

70

The flat spring 29 is held in the four depending arms 32 of the quick release member 33. This quick release member comprises not only the four depending arms 32, which support the flat spring and project interiorly of the upper frame 21, but also the portion 34, which is disposed upon the exterior surface of the upper frame 21. This portion 34 has the four depending arms 32 connected thereto in an offset manner, as shown at 35, there being an angular portion, shown at 36, between said portion 34 and the four depending arms 32, which hold the flat spring. The arms 32 project through the four apertures 37 in the upper side of the frame 21, it being apparent that said member 34, unless held against movement, is permitted to move horizontally, due to the fact that the apertures 37 are considerably larger than the portions 36, which connect member 34 with the arms 32.

80

It is apparent, also, that the member 34 may be moved horizontally in such manner that that part of the upper framing lying adjacent the apertures 37 is adapted to be disposed between the member 34 and the angular portions 36 to prevent vertical movement of the member 34 when same is held in this wedged position. Means for holding the member 34 in this wedged position with respect to the upper frame 21, is provided in the manual release member 38, which is pivoted, as at 39, in the upper framing, said manual release member having a cam-shaped engagement end 40 adapted to abut and engage an adjacent cam portion 41 formed upon one end of the quickly detachable member 33, or rather portion 34 thereof.

95

20 It is thought clear that manual manipulation of the quick release handle 38 will permit horizontal movement of the quick release portion 34 and the wedging of same or rather the angular portions 36 thereof, under the upper side of the framing 21. The cam fashioning of the manual lever and the abutment portion on the member 34 permits the holding of said quick release member in such wedged position when the wringer is in its normal position.

100

25 A conventional tension applying member is shown at 42, and comprises screw 43 which is threaded into the quick release portion 34 and adapted, at its lower end, to apply pressure upon the upper surface of the flat spring 29. The screw 43 also passes through an elongated slot in the frame, corresponding to the slots 37 for the arm members, as shown in Figure 5. It is apparent that same may be manually manipulated to apply proper tension.

110

30 Abutments 44 are shown on the flat spring 130

29, which prevent normal displacement of said spring from an operative position with respect to the depending arms 32. However, it might be stated that by complete withdrawal of the tension screw 43, the flat spring may be turned to such position as to permit its detachment from the upper framing.

With respect to the disposition of the manual release member 38, adjacent the quick release portion 34, in a manner to control the substantially horizontal movement thereof, it may be stated that such mounting of the quick release handle permits a very sensitive safety mechanism and one upon which only 15 a very slight manual pressure is necessary to release the member 34 and therefore the tension upon the wringer rolls applied by the flat spring.

Quick release mechanisms and safety release mechanisms are undoubtedly very old in the art and ordinarily include an upper framing member, a flat spring, or at least spring tensioning means, a quick release portion, a tensioning screw, and a manually operated release member. However, in all of the wringer mechanisms in which the above structure is shown and which, in terms is similar to applicant's, the manual release member is so associated with the quickly detachable member that when released, the release member moves vertically rather than both sidewardly and upwardly, as in the present instance. The effect of the movement in the present application with respect to the vertically movable quick release mechanism is as follows: In ordinary wringer construction, whenever the manual release member, or rather, the operation of the holding mechanism in connection therewith, completes the 25 tension connection between the quick release member and the upper wringer rolls, there is considerably more tension to be overcome by movement of the manually movable member than there is in the present instance, wherein 30 all the manual release member does is to prevent the quick release member from moving substantially horizontally and not vertically. This holding of the quick release member from movement horizontally permits a much 35 more delicate adjustment of the quick release mechanism, and therefore a very slight pressure upon the handle 38 to release the spring tension.

Quick release mechanisms are absolutely necessary upon wringers, for the purpose of safety and in a great many instances, these quick release mechanisms have required so much pressure to release the same that women, who have had their fingers caught between the wringer rolls have been unable to release the same. It is the chief aim of the applicant in the present wringer construction to provide a very sensitive adjustment of the safety mechanism, and one which 60 will permit the application of very slight

pressure to overcome the tension which is applied to the wringer rolls.

As far as the operation of the device is concerned, the manner of detaching the upper framing from the lower frame portion 70 is thought to have been clearly described, and as respects the application of tension to the wringer rolls, it is merely necessary to release the manually operated screw 42 in the conventional manner, thereupon move the 75 handle 38 to a position to wedge the quick release member 34, or rather the angular portion 36 thereof under the upper side of the frame 21, whereupon the screw 42 may be manually operated to apply the desired tension to the spring 29, which in turn applies pressure to the upper wringer rolls.

The cam 40 of the manual release handle 38 normally abuts the projection 41 upon the quick release portion 34 and holds same 85 wedged in a horizontal manner with respect to the upper frame. To release the tension, all that is necessary is to apply a slight pressure upon the handle 38, and to force the same to an offset position with respect to the 90 abutment 41, whereupon the quick release mechanism does not move vertically to release tension, but moves both horizontally and upwardly, thereby releasing tension upon the wringer rolls and preventing any possible accidents.

Attention is again called to the integral fashioning of the drain board to form the lower framework of the wringer, side portions of which provide the guideways for 100 the bearing blocks, which are removably mounted therein. As stated before, this fashioning of the lower framework of the wringer in connection with the drain board provides a sturdy and simple construction and one that 105 may be produced at a relatively low cost. Likewise, such fashioning permits the detachable mounting of the upper frame portion which carries the quick release mechanism.

What I claim is:

1. A wringer comprising a lower frame, upper and lower wringer rolls disposed therein, means for applying tension to the upper wringer roll including a flat spring, 115 an upper frame, safety release mechanism carried by the upper frame including a quick release member having a plurality of arm members projecting through enlarged apertures in the upper frame, said arms supporting the spring at their lower ends, portions of said arms being formed at an acute angle with respect to the quick release member and the upper frame to permit a wedged connection of the quick release member the depending 120 arms and the upper frame, a lever pivoted on a fixed part of the wringer having a cam member contacting with the release member for controlling the sideward movement of the quick release member either to a tensioned 125 130

- or released position, and a manually operated tensioning screw threaded into the quick release member, the lower end thereof abutting the spring to vary the tension thereof.
- 5 2. A wringer comprising a lower frame portion, an upper frame portion, and means for detachably connecting said upper portion to said lower portion including a projecting lug on one end of the lower frame, 10 a slot in the upper frame to receive said lug, aligned slots in the other ends of both upper and lower frames, and a key cooperating with said aligned slots to complete the assembly of the upper and lower frame portions.
- 15 3. A wringer comprising a lower frame, upper and lower wringer rolls, an upper frame mounted upon said lower frame, a spring adapted to apply tension to the rolls, a manually operated tension screw cooperat- 20 ing with the spring to control the degree of tension on said rolls, a quick release member carrying the tension screw, said release member being slidably mounted upon the upper frame and having offset wedge members pro- 25 jecting through the upper frame for coopera- tion with the sides of apertures in the frame, said apertures being elongated to permit horizontal and vertical movement of said wedges and corresponding vertical movement of 30 said quick release member and screw therein, and means for locking and unlocking the quick releasing member against and for lateral movement respectively.
4. A wringer comprising a lower frame, up- 35 per and lower wringer rolls, an upper frame mounted upon said lower frame, a spring adapted to apply tension to the rolls, a man- ually operated tension screw cooperat- 40 ing with the spring to control the degree of ten- sion on said rolls, a quick release member carrying the tension screw, said release member being slidably mounted upon the upper frame and having offset wedge members pro- 45 jecting therethrough for cooperation with the sides of apertures in the frame, said ap- 50 pertures being elongated to permit horizontal and vertical movement of said wedge mem- bers and corresponding vertical movement of said quick release member and screw there- 55 in, and a lever having a cam portion for engagement with a side of said quick re- lease member to control the sideward move- ment of the latter to wedged or unwedged position.
- 55 In testimony hereof, I have hereunto af- fixed my signature.

CLIFTON C. CAMMACK.
